WATER WELL PLANTER

Gabriel Lopez, 4352 W. Belden, Chicago, Ill. 60639

Filed Sept. 22, 1975, Ser. No. 615,315

Term of patent 14 years

Int. Cl. D11—02

U.S. Cl. D35—3 B

FIG. 1

FIG. 2

FIG. 3

FIG. 4

FIG. 5

FIG. 6

FIG. 1 is a perspective view of a water well planter showing my new design;

FIG. 2 is a front elevation thereof;

FIG. 3 is a side elevation thereof;

FIG. 4 is a side elevation taken from the opposite side as in FIG. 3;

FIG. 5 is a top plan view; and

FIG. 6 is a bottom plan view.

I claim:

The ornamental design for a water well planter, as shown.
